UNITED STATES PATENT OFFICE.

JAMES NEIL, OF LONDON, ENGLAND.

FURNACE-GRADE.

SPECIFICATION forming part of Letters Patent No. 616,133, dated December 20, 1898.

Application filed January 28, 1897. Serial No. 621,040. (No model.)

To all whom it may concern:

Be it known that I, JAMES NEIL, a citizen of the Dominion of Canada, residing at London, in the county of Middlesex, England, have invented certain new and useful Improvements in Furnace-Grates, of which the following is a full and complete specification, such as will enable those skilled in the art to which it appertains to make and use the same.

This invention consists of an improvement in rocking and dumping grates, and the object thereof is to provide improved grate-bars for grates of this class so as to secure better combustion and a greater steaming efficiency for boilers.

The invention is fully disclosed in the following specification, of which the accompanying drawings form a part, in which the separate parts of my improvement are designated by the same letters of reference in each of the views, and in which—

Figure 1 is a plan view of a part of a double grate constructed according to my invention; Fig. 2, a section on the line 2 2 of Fig. 1; Fig. 3, a transverse section on the line 3 3 of Fig. 2, and Fig. 4 a transverse section of my improved grate-bar.

In the drawings forming part of this specification, reference being made to Figs. 1 and 2, I have shown two of my improved grate-bars as employed in a double grate, and in the practice of my invention I provide a grate-bar which consists of two central vertical longitudinal webs A, two vertical side longitudinal webs a, and transverse webs a², by which the central longitudinal and side longitudinal webs are connected. As shown in Fig. 1, the transverse webs a² are arranged at a slight inclination to the longitudinal vertical webs; but this arrangement is not essential and may or may not be employed, and as thus constructed my improved grate-bar resembles in cross-section the form of a barrel, the central longitudinal webs A being much wider than the side longitudinal webs a and the transverse webs a² being elliptical in form. The side longitudinal webs a are provided on their outer surfaces with vertical ribs or projections a³, and the lower edges of said side longitudinal webs a are preferably provided with downwardly-directed notches or recesses a⁴. The central longitudinal webs A are also con-

nected by transverse webs a⁵, any desired number of which may be employed, and the inner walls of the said central longitudinal webs A are corrugated or fluted, as shown at a⁶. The object in thus forming the grate-bars is to provide perfect means for ventilation and for the free circulation of the air through and around the separate parts thereof and also to avoid the use of too much material, and the lower edges of the side longitudinal webs a need not necessarily be projected below the edges of the transverse webs a², as shown in Figs. 3 and 4.

In Figs. 1, 2, and 3 I have also shown improved devices for supporting the grate-bars when said grate-bars are used in a double grate. These devices consist of parallel side bars B, which are supported in any desired manner, and the outer ends of the grate-bars are provided with trunnions b, which pass through said side bars and are revoluble therein. The inner ends of said grate-bars are supported by horizontal parallel central bars D, which are connected by cross-rods d, and mounted in circular notches or recesses formed in the upper sides of the bars D are spindles d². The spindles d² are provided centrally with disks or plates d³, which are secured thereto and which are adapted to turn between the bars D, and the ends of the spindles d² are provided with downwardly-directed projections d⁴, which are beveled on their inner edges, as shown at d⁵, and are also provided with transverse notches or recesses d⁶, as shown in Fig. 3. The said spindles d² are also provided on their upper sides and at their ends with upwardly-directed lugs or projections d⁷, and the inner ends of the grate-bars are provided with vertical notches or recesses d⁸, which open downwardly, as shown in Fig. 3, and at the upper sides thereof with transverse slots or openings d⁹, which correspond with the lugs or projections d⁷. In connecting the inner ends of the grate-bars with the spindles d² the ends of said spindles, which are angular in form, as shown in Fig. 3, are passed into the angular notches or recesses d⁸ in the ends of the grate-bars and the lugs or projections d⁷ under the transverse slots or openings d⁹, and the ends of the spindles d² are thus caused to securely support the inner ends of the grate-bars, and

said grate-bars are compelled to turn with said spindles, and by turning one of said bars the corresponding spindle and the other bar will also be caused to turn, as will be readily 5 understood.

The grate-bars may be turned or dumped by applying a crank, crank-lever, or other device to the outer ends of said bars in the usual manner, and any preferred means may 10 be employed for this purpose.

I have not shown my improved grate-bar as applied to a single grate; but it will be understood that when my improved bar is thus used both ends thereof will be provided 15 with trunnions *b* in the usual manner, and said grate-bars may be turned or dumped, as hereinbefore described.

The central longitudinal webs *A* may also be grooved or corrugated on their outer surfaces, and the side longitudinal webs *a* may 20 be grooved or corrugated on their inner surfaces, and other changes in and modifications of the construction herein described may be made without departing from the spirit of 25 my invention or sacrificing its advantages.

The object of forming the vertical ribs or 30 projections *a*³ on the outer sides of the longitudinal side webs *a* and the notches or recesses *a*⁴ in the lower edges thereof and also in corrugating or fluting the central longitudinal ribs *A* is also to assist in breaking up the clinkers, and thus facilitating the dumping 35 of the bars and the passage of the ashes, clinkers, and other material therethrough, in addition to assisting in the ventilation thereof, and the disk or plate *d*⁸, secured to the spindle *d*, serves to clean the space between the central parallel supporting-bars *D* when 40 the grate-bars are turned, and it will thus be seen that I accomplish the object of my in-

vention by means of a device which is simple in construction and operation and which is also comparatively inexpensive.

Having fully described my invention, I claim as new and desire to secure by Letters Patent—

1. A dumping-grate, consisting of two sets of grate-bars, the outer ends of which are revolvably supported in parallel side bars, and the inner ends of which are supported in parallel central bars, said parallel central bars being provided with a revoluble spindle with which the inner ends of the grate-bars are detachably connected, and said spindle being provided with a disk or plate which is mounted thereon, centrally thereof, and which is adapted to turn between said parallel central bars, substantially as shown and described. 55

2. A dumping-grate, comprising two parallel side bars or supports, two central parallel side bars or supports, a spindle mounted in said central side bars or supports, and revoluble therein, and grate-bars, the outer ends of which are revolvably mounted in the side bars or supports, and the inner ends of which 60 are detachably connected with, and revoluble with said spindle, said spindle being also provided centrally with a disk or plate which is adapted to turn between said central supporting-bars, substantially as shown and described. 70

In testimony that I claim the foregoing as my invention I have signed my name, in presence of the subscribing witnesses, this 7th day of January, 1897.

JAMES NEIL.
